US00D957458S

(12) United States Design Patent (10) Patent No.: US D957,458 S
 McNulty (45) Date of Patent:  Jul. 12, 2022

(54) DISPLAY SCREEN OR PORTION THEREOF WITH ICON

(71) Applicant: salesforce.com, inc., San Francisco, CA (US)

(72) Inventor: Zachary Lee McNulty, Indianapolis, IN (US)

(73) Assignee: Salesforce, Inc., San Francisco, CA (US)

() Term: 15 Years

(21) Appl. No.: 29/768,584

(22) Filed: Jan. 29, 2021

(51) LOC (13) Cl. 14-04

(52) U.S. Cl.

USPC D14/492

(58) Field of Classification Search

USPC D14/485-95
